No. 11,690

March 16, 1880

UNITED STATES PATENT OFFICE.

JOHN E. HANIFEN, OF PHILADELPHIA, PENNSYLVANIA.

DESIGN FOR STOCKING FABRIC.

SPECIFICATION forming part of Design No. 11,690, dated March 16, 1880.

Application filed November 29, 1879. Term of patent 3½ years.

To all whom it may concern:

Be it known that I, JOHN E. HANIFEN, of the city and county of Philadelphia, and State of Pennsylvania, have originated and designed 5 an Ornamental Stocking Fabric, of which the following is a full, clear, and exact description, reference being had to the accompanying photographic illustration, making part of this specification.

10 *a* represents the plain ground of a piece of full-length or half hose.

15 *b* represents a series of parallel plain stitches, alternating with a series of parallel tuck-stitches, *c*. The plain stitches are continuous lines and the tuck-stitches broken lines. Tuck-stitches *d*, forming dots, are interposed between the plain stitches *b*.

The "clock" at the front of the hose or stocking is formed of a zigzag scroll, *e*, with a wave,

f, at each side, the scroll having a knot or head, 20 *e'*, and each wave a knot or head, *f'*, the whole forming a neat, tasty, and attractive design.

The fabric is produced by the usual plain-stitch and tuck cams.

What I claim as my invention is— 25

1. The ornamental design for a stocking fabric, consisting of the plain ground *a*, having continuous lines of plain stitches *b*, alternating with broken lines of tuck-stitches *c*, substantially in the manner above described 30 and illustrated.

2. The design for clock at the front of a stocking, as herein set forth and illustrated.

JOHN E. HANIFEN.

Witnesses:

JOHN A. WIEDERSHEIM,
A. P. GRANT.
